UNITED STATES PATENT OFFICE.

JACOB ABRAHAMSON, OF ASBURY PARK, NEW JERSEY.

HAND-BALL.

1,299,092.

Specification of Letters Patent.

Patented Apr. 1, 1919.

Application filed December 2, 1916. Serial No. 134,582.

To all whom it may concern:

Be it known that I, JACOB ABRAHAMSON, a citizen of the United States of America, and resident of Asbury Park, in the county of 5 Monmouth and State of New Jersey, have invented certain new and useful Improvements in Hand-Balls, of which the following is a specification.

This invention is an improvement in hand 10 balls; that is to say, an improvement in balls especially adapted for playing the well known game of "hand-ball." The game is a favorite form of exercise, and is commonly played in gymnasiums. The ball used is of 15 the conventional spherical form, and is generally composed of resilient material, such as rubber, though, in some instances, a pneumatic type of ball is employed. As a result of the ball being spherical in shape, it usually 20 rebounds with such regularity or precision that skilled players, noting the falling ball, can generally anticipate the direction in which it will bounce or rebound. Such being the case, the element of uncertainty 25 or chance is largely eliminated from the game, and this, naturally, detracts greatly from the interest in the game.

As the particular benefits to be derived 30 from hand-ball are the stimulation of the body through exercise, the development of agility, quickness of the eye, and analogous qualities, the object of the present invention is to so form a hand ball that its movements in rebounding from a rigid surface will be 35 of an uncertain character; that is to say, that its angle of rebound will not necessarily be substantially the same as the angle at which it strikes the rigid surface previous to the rebound, as is the case with a truly 40 spherical ball. Thus, the primary object of the invention is to so form a hand ball that a player cannot judge, with any degree of certainty, the direction of rebound of the ball, and, therefore, this keeps the players 45 on the alert, trains them to quicker action, and makes the game much more difficult to play, as well as encourages the acquirement of skill, than is the case when the game is played in the customary way, with a conventional ball.

Speaking generally, the invention embodies a hand ball, the exterior surface of which is provided with a plurality of faces, in contradistinction to the single face of a spherical ball, so that, when the ball strikes

a rigid surface, the direction of its bounce will be irregular and uncertain.

Features of the invention, other than those specified, will be apparent from the herein-after detailed description taken in conjunction with the accompanying drawing.

In the accompanying drawing I have illustrated different practical embodiments of the invention, but the constructions therein shown are to be understood as illustrative, 65 only, and not as defining the limits of the invention.

Figure 1 is a perspective view of a hand ball embodying the present invention, and

Fig. 2 is a like view of a modified form 70 which may be employed.

In the accompanying drawing, two forms of hand ball are shown, for the purpose of illustration. In the form of Fig. 1, the ball is shown as having fourteen sides or faces, 75 and, in Fig. 2, as having twelve faces. A ball made in accordance with the present invention may embody any number of faces desired, and may, in fact, be in the general form of a sphere, segments of which are cut 80 away to form substantially flat faces. The salient feature of the invention resides in the fact that the ball is provided with a plurality of faces so that, when it strikes a rigid surface, the exact direction of rebound cannot be anticipated. The players are thus required to be keyed up at all times during 85 the game, in order to follow the quick movements of the ball as it rebounds in unexpected directions.

The ball of this invention is preferably formed from solid rubber, although, if desired, it may be made in the form of a shell, the interior of which is inflated.

The polyhedron forms of the invention, 95 as illustrated in the drawing, have, in practice, given excellent results. By varying the number of the faces, and incidentally the size and angular relations thereof, the uncertainty of the bound can be determined 100 within reasonable limits, thereby enabling players, should they so desire, to progressively increase the difficulty of the game.

Having thus fully described the invention, what I claim as new, and desire to 105 secure by Letters Patent, is:

1. A hand ball provided with a plurality of substantially plane faces, whereby, when the ball strikes a rigid surface, it rebounds in an uncertain and unexpected direction. 110

2. A hand ball substantially in the form of a polyhedron, whereby, when the ball strikes a rigid surface, it rebounds in an uncertain and unexpected direction.
- 5 3. A toy composed of rubber or other resilient material and having upon its exterior surface one or more flat faces arranged and adapted to prevent the toy when thrown

against a stationary surface from returning in a predetermined direction. 10

Signed by me at New York city, N. Y., this 27th day of November 1916.

JACOB ABRAHAMSON.
